The ornamental design for a cap for puncture needle chip, as shown and described.

DESCRIPTION

FIG. 1 is a perspective view of the front, left and top of a cap for puncture needle chip showing our new design;

FIG. 2 is a front view thereof;

FIG. 3 is a top plan view thereof;

FIG. 4 is a bottom view thereof;

FIG. 5 is a left side view thereof;

FIG. 6 is a right side view thereof;

FIG. 7 is a rear view thereof; and,

FIG. 8 is a cross-sectional view at 8—8 shown in FIG. 6 thereof.
